Patented Sept. 24, 1912.

UNITED STATES PATENT OFFICE.

JOHN W. KUMMER AND GEORGE JORGENSEN, OF VANCOUVER, BRITISH COLUMBIA,
CANADA.

MEANS FOR SECURING RAILS TO TIES.

1,039,417.

Specification of Letters Patent Patented Sept. 24, 1912.

Application filed May 3, 1912. Serial No. 694,896.

To all whom it may concern:

Be it known that we, JOHN W. KUMMER and GEORGE JORGENSEN, citizens of the United States of America and the Dominion 5 of Canada, respectively, residing at Vancouver, in the Province of British Columbia, Canada, have invented a new and useful Means for Securing Rails to Ties, of which the following is a specification.

10 This invention relates to an improved rail seat and means for securing the rail to the same and the seat to the tie.

It is designed to be stamped out of sheet metal and to dispense with the use of spikes 15 as a securing means and to provide a greater area of contact of metal on the material of the tie.

This invention is supplementary to the fastening means on which a patent application 20 was filed on the 4th of March, 1912, under Serial No. 681,485, now pending before the Office.

The following specification particularly describes the invention, reference being 25 made to the drawings by which it is accompanied, in which:

Figure 1 is a perspective view of the rail seat. Fig. 2, a similar view of the movable clamp member. Fig. 3, a similar view of 30 the two side members of the seat securing means to the tie. Fig. 4, the bottom connection. Fig. 5, the taper cotter by which the seat is secured to the tie, and Fig. 6, a cross section through the rail showing its 35 attachment to the tie by this fastening.

Fig. 7 is a detail perspective view of one of the bolts employed in our device.

In these drawings 2 represents the rail and 3 the tie. The rail seat comprises a 40 plate portion 5 conforming approximately to the width of the tie and extending beyond the width of the rail flange on each side. On one side a portion 6 is sheared from it and bent upward to engage the upper side 45 of the rail flange. On the opposite side of the rail is secured an adjustable clamp 7, preferably of cast metal, shaped at one end to engage the upper side of the rail flange, and at the other having abutment serrations 8 to engage an upward projection 9 sheared from the plate 5 and upwardly turned to offer a square edge toward the rail. This clamp member 7 has an elongated hole 12 for a bolt 10 having a square neck 50 to fit a punched square aperture 11 in the

seat plate 5. Downwardly bent from each side of the plate 5 immediately under the rail flange, are portions 15 which divide below the bend and their ends are upwardly bent to form two cotter receiving hook members 16. Between these fit corresponding downwardly bent hook members 17 of the side securing members 18 which are inwardly turned, as at 19, below the depth of the tie and each has an aperture 20 at the 60 bend to receive the downwardly turned end 21 of the under connecting member 22.

When the taper cotters 25 driven between the upwardly turned ends 16 of the seat plate and the downwardly turned end of the 65 member 18 upwardly projecting from the under side of the tie, the seat plate is securely tightened onto the wood of the tie and this hold may be rendered more effective by having the ends of the seat plate or 70 their corners downwardly turned slightly, as at 14, to offer penetrating edges or points, which may be driven into the wood and will prevent lateral displacement of the seat plate on the tie. If found necessary, a 75 similar provision may be made along the edges of the under connection plate 22.

The seat plate being securely fastened on the tie, the rail flange may be inserted under the upwardly turned member 6, and the 80 clamp member 7 bolted tightly down on the flange on the other side and the rail will thus be securely but not too rigidly fastened down on the tie.

With the exception of the member 7, the 85 whole may be stamped out of sheet metal of such thickness as may be found satisfactory. If thought desirable, the ends of the hook members 16 and 17 may be produced beyond the width of the cotter and may be 90 bent inward and welded against the members 15 and 18 but this will not be necessary unless very thin plate is used.

Although specifically described as applicable to a wooden tie, the same means of 95 securing may be made use of with possibly slight modifications to a concrete tie.

Having now particularly described our invention we hereby declare that what we claim as new and desire to be protected in 100 by Letters Patent, is:

1. A means for securing a rail to a tie, said means comprising a plate of sheet metal having a portion sheared along three sides 105 toward the rail and bent upward from the 110

- plate to engage the upper side of the rail flange on one side, a similar sheared portion on the other side of the rail seat but bent upward only a short distance above the 5 plate, a clamp having abutment serrations to engage this upwardly bent portion, means for securing the clamp to the seat plate, and means for securing the seat plate to the underside of the tie.
- 10 2. A means for securing a rail to a tie, said means comprising a plate of sheet metal having a portion on one side of the rail seat sheared along the sides nearer to the rail seat and bent upward to engage the upper 15 side of the rail flange, a similar sheared portion on the other side of the rail seat but upwardly bent a short distance only above the face of the plate, a clamp member designed to bear on the rail flange and having 20 at the other end abutment notches to engage the edge of the upwardly bent portions of the plate and an elongated aperture to take a bolt passed through a square aperture in the plate close to the flange, and means for 25 securing the seat plate to the underside of the tie.
3. A means for securing a rail to a tie, said means comprising a plate of sheet metal having a portion sheared along three sides 30 nearer to the rail seat and bent upward to engage the upper side of the rail flange, a similar sheared portion on the other side of the rail seat but upwardly bent a short distance only above the face of the plate, a 35 square bolt aperture in the plate between this upwardly bent edge and the rail seat, hook members integral with and downwardly bent from the seat plate, said hook members being spaced apart to receive a 40 corresponding hook member projecting upward from the underside of the tie, and a connecting plate on the underside of the tie between the upwardly projecting hook members.
- 45 4. Means for securing a rail to a tie, said means comprising a bearing plate conform-
- ing approximately to the width of the tie and extending beyond the width of the rail flange on each side, said bearing plate having on one side fixed means for holding the 50 flange of the rail and on the other adjustable removable means for holding it down, a connecting plate extending across the underside of the tie, means for removably securing a side plate to each end of said connecting plate and means for connecting the side plates of the bottom to the side plates extending downward from the bearing plate at the top, said means comprising two cotter holding members on one spaced apart to receive a corresponding cotter holding member of the other and a taper cotter driven through the three cotter holding members. 55
5. A means for securing a rail to a tie, said means comprising a bearing plate conforming approximately to the width of the tie and extending beyond the width of the rail flange, said bearing plate having fixed means for holding down the flange of the rail on one side and adjustable removable 60 means for holding it down on the other, means for securing the rail seat to the tie comprising an under connecting plate having downwardly turned ends to enter apertures in side members bent under the connecting plate and extending upward beyond the half depth of the tie, said member being downwardly turned to form a cotter holding hook and designed to enter between two corresponding cotter holding hooks integral 65 with and downwardly projecting from the bearing plate and a taper cotter passing through the hook members. 70
- In testimony whereof we have signed our names to this specification in the presence 75 of two subscribing witnesses.
